KNITTING MACHINE

George O. Young, Robesonia, Pa., assignor to
Vanity Fair Mills, Inc., Reading, Pa., a corpora-
tion of Pennsylvania

Application October 15, 1945, Serial No. 622,321

23 Claims. (Cl. 66—86)

1

My present invention relates to knitting machines of the flat or tricot type.

Among the objects of my invention are the following:

1. To provide a simple, effective machine for knitting with non-swinging thread guide or guides by causing the needle hooks to traverse a double loop or figure 8 path, the lower loop passing into the sinkers and the upper loop passing the thread guides, the movements of the needle hooks through such path being such as to pass the threads on the guides on the up-strokes of the needles, hook the threads on the down strokes, draw them through the previously formed loops and knock-over;

2. To provide an improved thread take-up and let out mechanism which operates in time with the needles and keeps the thread taut at all times as the thread is drawn and slackened by the needles due to the peculiar path the needles take;

3. To provide improved thread guides and supports of such construction that the guides may be swung to different angular positions and held there when adjustments, or replacements of the guides become necessary by virtue of which when more than one thread guide set is used on the machine, the front set may be swung out of the way to give easy access to the other set, all without disconnecting the thread guide bars from the machine;

4. To provide a machine which is especially adapted to use the needles which constitute the invention of one Roy C. Amidon for which he filed an application for patent on August 18, 1944, Ser. No. 550,061, now Patent No. 2,403,961;

5. To provide a simple means for operating the needle tongues to open and close the needle hooks at the proper times;

6. To provide a novel resilient thread tension device over which the thread passes to the thread guides;

7. In general to provide a machine which will operate at high speed with a minimum of vibration;

8. To so position the thread guide (or guides) supporting means that the thread has its direction changed very close to the ends of the guide, thus dampening any fluttering effects of the yarn at this point;

9. To so position the thread guide (or guides) supporting means that it is necessary for the thread to run parallel to the guides and between them throughout the full length of the guides, thus further dampening of the threads is pro-

2

vided as the guides move in a horizontal direction.

10. To provide, because of the double loop needle path, sinkers which are stationary, thus further simplifying the construction of the machine.

Other objects will in part be obvious and in part will be pointed out hereinafter.

To the attainment of the aforesaid objects and ends the invention also resides in those novel details of construction, combination and arrangement of parts, which will hereinafter be first fully described and then will be specifically pointed out in the appended claims, reference being had to the accompanying drawings in which:

Fig. 1 is a front elevation of a machine embodying my invention, parts being broken away.

Fig. 2 is a top plan view of a portion of the same.

Fig. 3 is an end elevation, looking from right to left in Fig. 1.

Fig. 4 is a cross section on the line 4—4 of Fig. 1.

Fig. 5 is an enlarged, diagrammatic view showing the relative proportions of the parts necessary to cause the needle hooks to travel the double loop path indicated in Fig. 6.

Fig. 6 is a detail, enlarged cross section with the needle path and sinker nib path indicated throughout one cycle of the machine.

Figs. 6^a to 6¹⁵ respectively indicate the needle and nib positions with relation to the sinkers and the thread guides at the points 1 to 15 respectively of Fig. 6.

Fig. 7 is a view similar to Fig. 4, showing a second embodiment of my invention, when the sinkers are stationary.

Fig. 8 is a view similar to Fig. 6, with the needle path indicated with respect to the thread guides and the stationary sinkers.

Figs. 8^a to 8¹⁵ respectively indicate the needle positions at the points 1 to 15 in Fig. 8.

Fig. 9 is a detail view of one of the adjustable thread guide-bar-supporting arms.

Fig. 10 is a view similar to Fig. 9 of a modification.

Fig. 11 is a detail front elevation of some of the parts shown in Fig. 7.

Fig. 12 is a detail plan view hereinafter again referred to.

Fig. 13 is a view similar to Fig. 7, showing a modification that may be used to produce the needle path as shown in either Fig. 6 or Fig. 8.

In the drawings in which like numerals and letters of reference indicate like parts in all the

figures, 1 to 15 represent points in the figure 3 path of the needle hooks in Figs. 6 and 8.

The cross or spacing frames 16 are connected at suitable intervals and braced by pipes 147. Mounted in suitable bearings 64, in the cross frames 16, is a rotatable shaft 17, that may be the first motion shaft of the machine to which power is applied in any well known manner. A rock shaft 18 is also mounted in suitable bearings 65. The rock shaft 18 is bored transversely through its axis to provide bearings 19 for hollow shafts or rods 20 which carry bifurcated heads 21 on which the needle bar 22 is secured in any suitable way. The heads 21 also carry cross rods 27 to which the tongue bar 26 is attached. The cross rods 27 have movement in the direction of their axes, in the bifurcations of the heads. The rods 27 carry rollers 28 and are spring pressed, as at 29, in a direction to cause said rollers to contact stationary cams 32 and open the needle hooks. The cams 32 are carried by fixed channel bars 31 as best shown in Fig. 4. A stop nut 33 is provided on each rod 27 for the usual purpose.

The needles 24 have their bases 23 removably mounted on the needle bar 22 while the tongues 33 have their bases 25 removably mounted on the tongue bar 26. It should here be stated that the tongues are anchored in the hooks of the needles and close the hooks by being swung laterally with the anchorages as fulcrums. When the bases 25 are moved away from the bases 23 the needle hooks are closed and when the bases 25 are moved toward the bases 23 the needle hooks are opened.

Mounted on the first motion shaft 17 are eccentrics 34 that turn in straps 35 having caps 36. The rods 20 are pivoted to the straps 35 at 37.

A second eccentric carrying shaft 38 is journalled in bearings 63 and carries eccentrics 39, straps 40 and caps 41. The straps 40 are pivoted at 43 to arms 42 which are rigidly secured to the rock shaft 18 as at 47. The shaft 38 is driven from the shaft 17 at twice the speed of said shaft 17 by a sprocket and chain connection 44, 45, 46.

The sinkers 49 are mounted on a fixed support or sinker bar 48. In the embodiment of my invention illustrated in Figs. 1 to 6 the sinker nibs 54 are endwise movable over the sinkers 49. The sinker nibs are mounted on a sinker bar 53 that is secured to the heads 52 which heads are carried on hollow rods 51 that pass through bearing apertures in a fixed shaft 50 and are pivotally connected at 59 to the straps 57 which, with their caps 58 embrace eccentrics 56 on a third rotatable shaft 55. The shaft 55 is driven from the shaft 17 at the same speed by a sprocket and chain drive 60, 61, 62.

66 and 67 indicate fixed non-rotatable rods that carry the thread guides. These rods are provided with collars (in the preferred construction) 68 having splines 69 to fit the grooves in the thread-guide-bar-carrying arms 70 and 71 later again referred to.

Other rods 73, 74 are fixedly held in the frame members 16. The rods 66, 67, 73 and 74 may be held from turning by means of set screws 72. The rod 73 is set above and, preferably, somewhat forward of the rod 74 and these rods carry spring metal plates 75 and 76 respectively, the outer edges of which are curved down to permit the threads T¹ and T² respectively to slide over without cutting. The resilient plates 75, 76 act

as thread tensioning means and exert a uniform tension throughout their entire lengths.

The shaft 78 of the lower beam 77 lies in bearings 79 in the end frames 16 while the shaft 81 of the upper beam 80 lies in bearings 82 in the frames.

The thread take-up and let-off mechanism, which constitutes a part of my invention, comprises a stub shaft 83 that is journalled in suitable bearings in an end frame 16 and carries a spur gear 95 that meshes with a spur 92 on the shaft 91 of the lower let-off and take-up roller 90. A bell crank lever 88 is pivoted on the shaft 83. Its short arm carries the shaft 91 while its long arm carries a cam-engaging roller 114. An upper stub shaft 84 has a gear 86 that meshes with a gear 95 on the shaft 94 of the upper take-up and let-off roller 93. The shaft 94 is journalled in the short arm of a second bell crank lever 89, the lever 89 being pivoted on the shaft 84 and carrying on its long arm a cam-engaging roller 115. The shafts 83 and 84 are connected by a sprocket and chain drive 87. The shaft 83 is driven from shaft 55 by mechanism best shown in Fig. 3 by reference to which it will be seen that a worm 101 on shaft 55 meshes with a worm gear 100 on a counter shaft 97 that is journalled in bearings 98 and carries a worm 99 which meshes with a worm gear 96 on the shaft 83.

A spur gear 102, on shaft 55, meshes with a spur gear 103 on a short shaft 104 that is journalled in bearings in an end frame and in a bracket 105. The shaft 104 has a worm 106 that meshes with a worm gear 111 on the pattern wheel shaft 107. The shaft 107 is journalled in suitable bearings 108 and carries the pattern wheels 109 and 110 for the front and rear thread guides 70 and 71 respectively.

The rollers 114, 115, Figs. 2 and 4, engage cams 112, 113, respectively, against which the rollers are held by springs 117.

118 is the cloth guide roller over which the cloth passes to a suitable take-up roll (not shown).

Front thread T¹ is taken from the upper beam, passed around the roller 93, over an upper guide bar 121 and from thence over the upper tension plate 75 and down through the eye of the front guide 124 while back thread T² is passed from the lower beam around roller 98, over a guide bar 122 and over the lower tension plate 76 down through the eye of the back guide 125.

Referring now to Fig. 10 it will be seen that instead of the spline and groove connection between the arms (70 or 71) which carry the thread guide bars, the arms 123 are adjustably held on the supporting rod 66 (and if desired 67) by at least one set screw 146. Each arm 123 has a dovetail slot or groove 119 to receive the dovetail 120 on the slide block 151 to which slide blocks the guide bar 145 is secured. The guide bars 145 (front and back) have extension rods 148 at their ends. The rods 148 at one end carry rollers 149 (see Figs. 1 and 2) that are held in engagement with the pattern wheels 109, 110 by the springs 151 attached to brackets 150 on the other ends of the rods 148 and anchored to a frame 16.

Referring now to Figure 7 showing a second embodiment of the invention, it will be seen that the shaft 17 is provided with eccentrics 126 around which are straps 127 and caps 128, each strap 127 being pivoted at 139 to a link 132 whose other end is pivoted at 138 to the strap 130 of an eccentric 129 on the shaft 38, the usual cap 131 being provided. A short arm 133 is secured

to the rock shaft 18 and has a slot 134. The pivot 136 is preferably carried by a block 137 that is adjustably secured in the slot 134.

In the embodiment shown in Fig. 7, each sinker 140 has an integral nib 141, while a second or auxiliary nib 144 cooperates with the nib 141 and sinker 140. The nibs 144 are carried on a nib bar 142, carried on arms 143 secured to suitable supports as, for instance, the front rod 66.

In Fig. 13 the link 135 is shown non-adjustably pivoted to the arm 133a.

It should be understood that the eccentric means for rocking shaft 18, reciprocating the needle and tongue bars, the sinker nib bar and operating the thread take-up and let-off rollers, etc. are duplicated at each end of the machine. Also the proportions or dimensions of parts given in Figs. 5 and 13 are only approximate and may be somewhat varied to attain the double loop or figure 8 shape of the path of travel P of the needle hook.

By reference to Figs. 5, 6 and 6⁰ to 6¹⁵ inclusive, the operation of the first embodiment of my invention will, it is thought, be clear to those skilled in the art. With the needle 24 (and tongue 33) at its lowest point (Fig. 6⁰) it will have drawn the threads T¹ and T² through the previously formed loop L¹; as the needle leaves the zero position and begins to rise, the shaft 18 is rocked counter-clockwise in Fig. 5, thus moving the eye of the needle to the left. This movement to the left continues until a point approximately midway between points 2 and 3 in Fig. 6, i. e., between the position of Figs. 6² and 6³, is reached, whereupon the eye of the needle begins to move to the right in Fig. 6, i. e., shaft 18 begins to rock clockwise, and this clockwise movement continues until the needle reaches the top of its stroke at point 8, Fig. 6 (Fig. 6⁸). From that point 8, as the needle starts down shaft 18 is rocked counter-clockwise in Fig. 5 until point 11 is reached (Fig. 6¹¹), whereupon shaft 18 begins to rock clockwise again and continues to do so until point 13 in Fig. 6 (Fig. 6¹³) is reached when shaft 18 begins to turn counter-clockwise again and continues to do so until the zero point Fig. 6 (Fig. 6⁰) is again reached, completing a knitting cycle. It will then be seen that in passing through one cycle of operation the hook of the needles moves in a path P resembling a closed figure 8.

As the needle starts to rise the sinker nib 54 advances with a continuous motion (as does the needle also), the different positions of the nib 54 at points corresponding to the needle hook position-points in Fig. 6 are indicated by similarly numbered points on a horizontal line H. The positions of the nib in Figs. 6⁰ to 6¹⁵ inclusive correspond to the position points 1 to 15 on line H in Fig. 6. Referring particularly to Figs. 6⁰ to 6¹⁵ inclusive, it will be seen that as the needle rises from the position of Fig. 6⁰, before it rises sufficiently so it would lift the loop L¹, the nib 54 will have advanced over that loop (Figs. 6¹, 6²). As the needle rises the thread about the needle will be held down as a second loop L² (Fig. 6³) is formed. After the needle shall have risen past the position shown in Fig. 6⁴ sufficiently to clear the thread guides 125, 124 (see Fig. 6⁵) the guides are racked by the pattern wheels so that on the down stroke of the needle it will hook the threads (Figs. 6¹⁰, 6¹¹ and 6¹²) to draw the threads through the second loop L². As soon as the point of the hook reaches the sinker nib (Fig. 6¹²) the roller 28 (Fig. 5) will ride on cam 32 and move over (right to left, Fig. 5) the tongue

bar 26 and close the gap between the point of the hook and the shank of the needle. This gap remains closed until the thread has been drawn through the loop L² (Fig. 6¹⁴) after which it is again opened as the head 21 is tilted to the left in Fig. 5 in moving from position of Fig. 6¹⁴ to position Fig. 6¹⁵. After reaching the position shown in Fig. 6⁷ the nib 54 begins its return movement so as to leave the threads between the guides and needles free.

The operation of the embodiment of my invention shown in Figs. 7, 8, and 8⁰ to 8¹⁵ is essentially the same as the first embodiment, the position of the gap between the two nibs 141 and 144 being so located that when the needle drawing down the thread reaches the position shown in Fig. 8¹³ it will line up with the gap and the threads will be clear of the sinkers.

As will be seen by reference to Figs. 6³ to 6¹³ the loops L², L¹ (knit of fabric) are moved to the right from the position of Fig. 6³ to the position of Fig. 6⁸ and are then moved back again to about the position shown in Fig. 6¹¹, due to the lateral movements of the needle. This results in a pull-and-slab action on the threads coming from the beams via the thread guides and must be compensated for. In order to accomplish this the take-up and let-out mechanism shown in the drawings and hereinbefore described has been devised. The cams 112, 113 are so cut as to cooperate with the needle operations and movements, that when the threads at the needles tend to slacken the arms or levers 88, 89 will be rocked to move the rollers toward the beams to take up slack and away from the beams to let out the thread as required. The resilient plates 75, 76 take the place of the usual spring loaded tension rods heretofore employed in tricot machines, to take care of slight variations in the thread tensions.

The arms 70 and 71, respectively, carry the bars 121^x and 122^x on which the thread guides 124 and 125, respectively, are mounted.

The thread guides 124 and 125 have eyes 124^x and 125^x respectively. The guides only move longitudinally of the machine and do not swing back and forth.

While I have shown and described a new and improved thread guide bar mounting for a knitting machine and also a new and improved tensioning means for a knitting machine, I make no claim per se to the same as they comprise the subject matter of divisional applications filed the 10th day of September, 1946, Serial No. 695,920, now Patent Number 2,451,187, and the 10th day of October, 1946, the Serial No. 702,511, now Patent Number 2,442,796.

From the foregoing description taken in connection with the accompanying drawings it is thought the construction, operation and advantages of my machine will be clear to those skilled in the art to which it appertains.

What I claim is:

1. In a knitting machine; stationary sinkers; thread guides which move only longitudinally of the machine above the sinkers; sinker nibs; hook knitting needles mounted to move up and down through the sinkers and nibs; and means causing the needle hooks to travel in a closed figure eight path in part within the sinkers and in part between and above the eyes of the thread guides, the movement of the needles being such that the backs of the needles will engage the thread between the guides on the up strokes of the needles and the needles will hook the thread on

the down strokes; and means to close the needle-hooks as the points of the hooks enter the sinkers on the down strokes of the needles, said means to close the needle hooks comprising needle closing tongues carried by the needles; and means to operate said tongues in timed relation to the operations of the needles for knitting purposes.

2. In a knitting machine; stationary sinkers; thread guides which move only longitudinally of the machine above the sinkers; sinker nibs; hook knitting needles mounted to move up and down through the sinkers and nibs; and means causing the needle hooks to travel in a closed figure eight path in part within the sinkers and in part between and above the eyes of the thread guides, the movement of the needles being such that the backs of the needles will engage the thread between the guides on the up strokes of the needles and the needles will hook the thread on the down strokes; and means to close the needle-hooks as the points of the hooks enter the sinkers on the down strokes of the needles, said means which causes the needles to move including a rock shaft having bearing holes through it, shafts reciprocative in said bearing holes and carrying said needles, means to reciprocate said shafts in said bearing holes, and means to rock said rock shaft in timed relation to the reciprocations of said needle-carrying shaft for purposes described.

3. In a knitting machine; stationary sinkers; thread guides which move only longitudinally of the machine above the sinkers; sinker nibs; hook knitting needles mounted to move up and down through the sinkers and nibs; and means causing the needle hooks to travel in a closed figure eight path in part within the sinkers and in part between and above the eyes of the thread guides, the movement of the needles being such that the backs of the needles will engage the thread between the guides on the up strokes of the needles and the needles will hook the thread on the down strokes; and means to close the needle-hooks as the points of the hooks enter the sinkers on the down strokes of the needles, said means which causes the needles to move including a rock shaft having bearing holes through it, shafts reciprocative in said bearing holes and carrying said needles, means to reciprocate said shafts in said bearing holes, and means to oscillate said rock shaft twice to each reciprocation of said needle-carrying shaft and in timed relation to the same.

4. The machine of claim 2 wherein needle closing tongues are carried by the needles; and means are provided to operate said tongues in timed relation to the operations of the needles for knitting purposes.

5. The machine of claim 3 wherein needle closing tongues are carried by the needles; and means are provided to operate said tongues in timed relation to the operations of the needles for knitting purposes.

6. In a knitting machine wherein hook knitting needles, thread guides which move only longitudinally of the machine, stationary sinkers, and sinker nibs are employed, the improvement which includes means to cause the needles to pass up from the sinkers and through the thread guides without hooking the threads and then pass back to the sinkers and hook the threads on the return trip, said means including an oscillatable shaft having bearing apertures passing transversely through the shaft and intersecting the axis thereof, needle-carrying shafts mounted to be reciprocated in said apertures, and means to

reciprocate said needle-carrying shafts and oscillate said oscillatable shaft, there being two oscillations of said oscillatable shaft to one reciprocation of said needle carrying shaft.

5. In a knitting machine employing thread guides, stationary sinkers, sinker nibs, hook needles and tongues therefor, the improvement which includes an oscillatable shaft bored transversely along parallel lines intersecting the axis of the shaft to form bearings; a needle bar; shafts passing through said bearings and carrying said needle bar; eccentric and strap connections so as to reciprocate said needle-bar-carrying shafts; means to oscillate said oscillatable shaft in timed relation to the reciprocations of said needle-bar-carrying shafts to effect the path of travel of the needles so as to pick up thread on the down strokes only of the needles; and means to close the needle hooks after the thread has been hooked and before the point of the hook enters a previously knit loop.

8. In a knitting machine the improvement which includes; a first eccentric shaft and a second eccentric shaft; means to rotate said shafts with the second shaft making two revolutions to one of the first shaft; an oscillatable shaft having transverse bearing apertures through it; needle-bar-carrying shafts reciprocatably mounted in said transverse bearing apertures; eccentric on said first shaft; operative connections between said eccentric and said needle-bar-carrying shafts; a needle bar carried by said needle-bar-carrying shafts; hook needles mounted on said bar; eccentric on said second shaft; arms on said oscillatable shaft; operative connections between said last named eccentric and said arms.

9. The improvement of claim 8 wherein a tongue bar is carried by said needle-bar-carrying shafts; tongues carried by said tongue bar and cooperating with said needles; and means to move said tongue bar on said needle-bar-carrying shafts to close and open the needle hooks in timed relation to the needle movements during the knitting cycle.

10. In a knitting machine having thread guides which move only longitudinally of the machine, sinkers, and nibs; two eccentric shafts each having eccentric and one shaft rotating at twice the speed of the other; an oscillatable shaft having bearings passing diametrically through the same; a set of needle-bar-carrying shafts reciprocative in said bearings; a needle bar carried by said last named shafts; eccentric strap connections between said reciprocative shafts and the eccentric on the slower of said eccentric shafts; arms on said oscillatable shaft; operative connections between said arms and the eccentric on the faster of said eccentric shafts by virtue of which for each complete reciprocation of said set of reciprocative shafts said oscillatable shaft will be given two complete oscillations for purposes described; hook needles on said needle bar; and means for closing the hooks of said needles while they pass into the spaces between the blades of the nibs and sinkers.

11. In a knitting machine having thread guides which move only longitudinally of the machine, sinkers, and nibs; two eccentric shafts each having eccentric and one shaft rotating at twice the speed of the other; an oscillatable shaft having bearings passing diametrically through the same; a set of needle-bar-carrying shafts reciprocative in said bearings; a needle bar carried by said last named shafts; eccentric strap con-

nections between said reciprocative shafts and the eccentrics on the slower of said eccentric shafts; arms on said oscillatable shaft; operative connections between said arms and the eccentrics on the faster of said eccentric shafts by virtue of which for each complete reciprocation of said set of reciprocative shafts said oscillatable shaft will be given two complete oscillations for purposes described; hook needles on said needle bar; means for closing the hooks of said needles while they pass into the spaces between the blades of the nibs and sinkers, said last named means including a tongue-carrying bar carried by said set of reciprocative shafts; and means cooperating with said tongue-carrying bar for operating the same in timed relation to the reciprocations of said set of reciprocative shafts.

12. In a knitting machine having thread guides which move only longitudinally of the machine, sinkers, and nibs: two eccentric shafts each having eccentrics and one shaft rotating at twice the speed of the other; an oscillatable shaft having bearings passing diametrically through the same; a set of needle-bar-carrying shafts reciprocative in said bearings; a needle bar carried by said last named shafts; eccentric strap connections between said reciprocative shafts and the eccentrics on the slower of said eccentric shafts; arms on said oscillatable shaft; operative connections between said arms and the eccentrics on the faster of said eccentric shafts by virtue of which for each complete reciprocation of said set of reciprocative shafts said oscillatable shaft will be given two complete oscillations for purposes described; hook needles on said needle bar; means for closing the hooks of said needles while they pass into the spaces between the blades of the nibs and sinkers, said last named means including heads on said set of reciprocative shafts; tongue-bar-carrying rods movably mounted on said heads, a tongue-carrying bar carried by said rods, tongues on said tongue-carrying bar and cooperatively associated with said needles; and means to move said tongue-bar-carrying rods back and forth to close and open the hooks of said needles in timed relation with the movements of the same.

13. A machine according to claim 12 wherein stationary cams are engaged by said tongue-bar-carrying rods when the needle hooks are drawing threads through previously knit loops.

14. A machine according to claim 12 wherein is provided a stationary shaft having bearings; a third eccentric shaft; a set of nib-bar-carrying shafts reciprocative in said stationary shaft bearings and on which said nibs are mounted; a set of eccentrics on said third eccentric shaft and operatively connected to said nib-bar-carrying shafts; means for turning said third eccentric shaft at the same speed as that of the slower of the first mentioned shafts.

15. A machine according to claim 12 wherein is provided a stationary shaft having bearings; a third eccentric shaft; a set of nib-bar-carrying shafts reciprocative in said stationary shaft bearings and on which said nibs are mounted; a set of eccentrics on said third eccentric shaft and operatively connected to said nib-bar-carrying shafts; means for turning said third eccentric shaft at the same speed as that of the slower of the first mentioned eccentric shafts; at least one beam and a thread take-up and let-out mechanism for the same, which mechanism includes bell crank levers carrying a roller around which the thread from the beam passes; and cams on

said third eccentric shaft to engage said levers to operate the same in timed relation to the operations of the needles.

16. In a knitting machine having thread guides which move only longitudinally of the machine, sinkers, and nibs: two eccentric shafts each having eccentrics and one shaft rotating at twice the speed of the other; an oscillatable shaft having bearings passing diametrically through the same; a set of needle-bar-carrying shafts reciprocative in said bearings; a needle bar carried by said last named shafts; eccentric strap connections between said reciprocative shafts and the eccentrics on the slower of said eccentric shafts; arms on said oscillatable shaft; operative connections between said arms and the eccentrics on the faster of said eccentric shafts by virtue of which for each complete reciprocation of said set of reciprocative shafts said oscillatable shaft will be given two complete oscillations for purposes described; hook needles on said needle bar; means for closing the hooks of said needles while they pass into the spaces between the blades of the nibs and sinkers; at least one beam and a take-up and let-out mechanism for the beam, which mechanism includes a set of bell crank levers carrying a roller around which the thread from the beam passes; and cams on said third rotatable shaft with which cams said levers engage to be operated by the cams in timed relation to the movements of the needles.

17. In a knitting machine, the improvement which includes: a first eccentric shaft and a second eccentric shaft; means to rotate said shafts with the second shaft making two revolutions to one of the first shaft; an oscillatable shaft having bearing apertures; needle-bar-carrying shafts reciprocative in said bearings; eccentrics on said first shaft; operative connections between said eccentrics and said needle-bar-carrying shafts; a needle bar carried by said needle-bar-carrying shafts; hook needles mounted on said bar; eccentrics on said second shaft; arms on said oscillatable shaft; operative connections between said last named eccentrics and said arms; a tongue bar carried by said needle-bar-carrying shafts; tongues carried by said tongue bar and cooperating with said needles; and means to move said tongue bar on said needle-bar-carrying shafts to close and open the needle hooks in timed relation to the needle movements during the knitting cycle.

18. In a knitting machine having thread guides which move only longitudinally of the machine, sinkers, and nibs: two eccentric shafts each having eccentrics and one shaft rotating at twice the speed of the other; an oscillatable shaft having bearings; a set of needle-bar-carrying shafts reciprocative in said bearings; a needle bar carried by said last named shafts; eccentric strap connections between said reciprocative shafts and the eccentrics on the slower of said eccentric shafts; arms on said oscillatable shaft; operative connections between said arms and the eccentrics on the faster of said eccentric shafts by virtue of which for each complete reciprocation of said set of reciprocative shafts said oscillatable shaft will be given two complete oscillations for purposes described; hook needles on said needle bar; means for closing the hooks of said needles while they pass into the spaces between the blades of the nibs and sinkers, said last named means including heads on said set of reciprocative shafts, tongue-bar-carrying rods movably mounted on said heads, a tongue-carrying bar carried by said

11

rods, tongues on said tongue-carrying bar and cooperatively associated with said needles; and means to move said tongue-bar-carrying rods back and forth to close and open the hooks of said needles in timed relation with the movements of the same.

19. A machine according to claim 18 wherein is provided stationary cams engaged by said tongue-bar-carrying rods when the needle hooks are drawing threads through previously knit loops.

20. A machine according to claim 18 wherein is provided a stationary shaft having bearings; a third eccentric shaft; a set of nib-bar-carrying shafts reciprocative in said stationary shaft bearings and on which said nibs are mounted; a set of eccentrics on said third eccentric shaft and operatively connected to said nib-bar-carrying shafts; means for turning said third eccentric shaft at the same speed as that of the slower of the first mentioned eccentric shafts; at least one beam and a thread take-up and let-out mechanism for the same, which mechanism includes bell crank levers carrying a roller around which the thread from the beam passes; and cams on said third eccentric shaft to engage said levers to operate the same in timed relation to the operations of the needles.

21. In a knitting machine having thread guides which move only longitudinally of the machine, sinkers, and nibs: two eccentric shafts each having an eccentric and one shaft rotating at twice the speed of the other; an oscillatable shaft having bearings; a set of needle-bar-carrying shafts reciprocative in said bearings; a needle bar carried by said last named shafts; eccentric strap connections between said reciprocative shafts and the eccentrics on the slower of said eccentric shafts; arms on said oscillatable shaft; operative connections between said arms and the eccentrics on the faster of said eccentric shafts by virtue of which for each complete reciprocation of said set of reciprocative shafts said oscillatable shaft will be given two complete oscillations for purposes described; hook needles on said needle bar; means for closing the hooks of said needles while they pass into the spaces between the blades of the nibs and sinkers; at least one beam and a take-up and let-out mechanism for the beam, which mechanism includes a set of bell crank levers carrying a roller around which the thread from the beam passes; and cams on said third

12

5 rotatable shaft with which cams said levers engage to be operated by the cams in timed relation to the movements of the needles.

22. In a knitting machine wherein knitting needles with hinged hook closing tongues are employed and wherein means are provided for reciprocating the needles and tongues and opening and closing the hooks, the improvement which includes: a rock shaft having bearing apertures; rods reciprocative in said bearing apertures; a needle bar carried by said rods; a main eccentric shaft; eccentrics on said main eccentric shaft; eccentric straps connecting said eccentrics with said rods to reciprocate the same; at least one other eccentric on said main eccentric shaft; a second eccentric shaft; at least one eccentric on said second eccentric shaft; eccentric straps for each of the last two mentioned eccentrics; a cross link pivoted at its ends to said last named eccentric straps and having an intermediate link-arm integral therewith; an arm secured to said rock shaft and pivoted to said intermediate link-arm; and means for driving said second eccentric shaft at twice the speed of the first mentioned eccentric shaft.

23. A machine according to claim 22 wherein there is provided a tongue bar carried by said rods; hook needles on said needle bar; tongues on said tongue bar; and means for effectively 30 operating said tongue bar to cause the tongues to open and close the needle hooks in timed relation to the knitting cycle.

GEORGE O. YOUNG.
